CHROMATIC HARP

Walter Vantwiller A. Franklin, New York, N. Y.

Application December 2, 1937, Serial No. 177,813

6 Claims. (Cl. 84—264)

This invention relates to improvements in harps.

An important object of this invention is to provide a harp capable of producing chromatic tones and on which music written in major or minor scale can be played without difficulty.

Another object of the invention is to provide a harp which is simple in operation so that one skilled in the piano or organ can readily acquire proficiency in playing this harp.

A further object of the invention is to provide improved sounding means, tone control, and key indicating means to simplify the playing of music written in major or minor scale.

Additional objects and advantages of the invention will hereinafter become more readily apparent from the following specification of which the drawing forms a part, and wherein:—

Figure 1 is a side elevational view of the invention.

Figure 2 is a vertical sectional view on the line 2—2 of Figure 1, and

Figure 3 is a horizontal sectional view on the line 3—3 of Figure 1.

Referring more particularly to the drawing wherein like reference characters indicate like or corresponding parts throughout, 10 designates generally the harp comprising the frame portion composed of the pedestal 11, back 12, neck 13, and pillar 14.

In the conventional harp the upper or front part 15 of the back 12 forms the sound board. As seen in Figures 2 and 3 the pedestal 11, pillar 14, and back 12 are hollow to form additional resonant chambers. Harp 10 is also provided with a vertically disposed sound box 16 having its open side abutting the inner side of pillar 14 as seen in Figure 3, and extending between neck 13 and sound board 15 of the back 12 on the right side of harp 10, looking in the direction indicated by the arrows 2—2 in Figure 1.

Secured to the middle of the sound board portion 15 and extending one-half the length thereof is an angular member 17 having its upwardly extending side 18 provided with uniformly arranged apertures 19 comprising openings terminating in slots. The openings are adapted to receive the knotted ends of the harp strings 20 which are held therein by the knotted ends engaging the slotted portions. Strings 20 are stretched across the open part 21 of harp 10 and across the left side of box 16 and are attached to the wrest pins 22 which are mounted in two rows on the neck 13 and by means of 55 which strings 20 are tuned.

The harp 10 may be made with from three to eight octaves. It may be manufactured with as many as eighty-eight strings, but preferably is composed of sixty-two strings, as illustrated comprising slightly more than five octaves.

Extending the length of opening 21 and attached to the underside of neck 13 and to the left side of box 16 is the strip 23 which is marked as indicated at 24 to correspond to the keyboard of a piano. A string 21 extends over each of the key marks 24 and is tuned to correspond to the key over which it is placed so that the musician can more readily pick the strings with his fingers using strip 23 as a guide, in order to make possible the playing of music written in major and minor scale. A damper head 25 is provided which is pivotally mounted in ear 26 on sound board 15 and in an opening in pillar 14 to support it transversely of the springs 20 on the opposite side to box 16. Damper head 25 is provided with an angular lug 27 as best seen in Figure 2 which is connected to the vertically disposed rod 28 which extends down into pedestal 11. Pedestal 11 is provided with an internally disposed depending partition 29 on which 25 is pivotally mounted a lever 30 having one end connected to rod 28 and the opposite end connected to pedal lever 31 which is pivoted at its end 32 to the partition 29. Pedal 31 has its opposite end projecting through a vertical slot 33 30 in the left side of pedestal 11, and mounted thereon is a roller 34 forming a foot pedal. A leaf type spring 35 has one end engaging pedal 31 and the opposite end resting on the bottom of pedestal 11 to hold pedal 31 in an elevated position as illustrated. When in this position rod 28 is in its lowered position holding damper head 25 out of engagement with strings 20. When pedal 34 is pressed down lever 30 is rocked raising rod 28 and swinging damper head 25 into 40 engagement with strings 20. Damper head 25 has a felt strip 36 secured to its inner side to engage strings 20.

Mounted on the underside of pedestal 11 are the rubber pads 37 on which harp 10 is partially supported and which prevent the harp from sliding while being played. Mounted under the horizontal portion of back 12 is a roller 38 which cooperates with pads 37 to support the harp 10, and on which harp 10 may be rolled by tilting it 50 to raise pads 37.

Attached to pillar 14, as seen in Figure 3, is a bracket 39 to which is removably attached arm 40 which supports a music rack 41.

Sound box 16 is provided with openings 42; 55

sound board 15 with openings 43; and pedestal 11 with the elongated openings 44 by which the tones produced by strings 20 are released.

15 The sound box 16 which connects with pillar 14 and sound board 15 produces the chromatic tones necessary for music played in the major or minor scale.

10 The harp 10 is played by picking the base strings, which are the long strings and which extend along the side of the box 16 with the left hand only, while the "G" string below middle "C" and the strings above it may be played with both hands but preferably with the right hand on the right side of the harp, or the side to which box 16 is secured. Damper head 25 is operated by the foot engaging pedal 34 to control the tone vibrations of strings 20, the roller 34 preventing the harp from being pushed away from the artist when the roller is depressed. The harp 10 due 20 to its construction will stay in tune indefinitely, and is adapted to be tuned to correspond to a piano as heretofore explained. The artist preferably sits or stands behind the harp with the right shoulder resting against the back 12 so that 25 the head is to the left of the harp and conveniently positioned for watching the strip or guide 23, while playing. In this position, the left hand is free to conveniently pick the base, or long strings, on the left side of the harp 10, while the 30 treble strings, or short strings, can be picked with the right hand on the opposite or right side of the harp. The left hand will be usually disposed beneath strip 25, but if necessary, where the treble strings alone are being played, the left hand may 35 be used to pick these strings above strip 25.

Various changes and modifications may obviously be resorted to without departing from the invention as hereinafter claimed.

I claim as my invention:—

40 1. A harp provided with a hollow pillar, pedestal, and back forming resonant chambers, and a sound box disposed between the neck and back of the harp and lying along one side of the strings, said sound box having a plurality of openings in one side facing the strings and communicating with the interior forming the sound chamber.

45 2. A harp provided with a hollow back, pedestal and pillar forming sound chambers, a sound box disposed along one side of the strings and connected to said back, pedestal, and pillar to co-act

therewith to produce chromatic tones, and a bar arranged transversely of the strings and marked adjacent each string to correspond with a piano keyboard to permit said strings to be played by chords corresponding to a piano.

5 3. In a harp, a sounding box adapted to be disposed along one side of certain of the strings, said sounding box comprising spaced panels connected along one side, the opposite side, top and bottom being open, said open side, top and bottom 10 being positioned to rest flush against the pillar, neck and sound board, respectively, of the harp and to communicate with said parts in producing deep melodious tones, and the panel of said sounding box disposed adjacent to the strings 15 being provided with a plurality of sound releasing openings.

4. A harp provided with a pedestal, pillar, back and neck, said pillar, back and neck forming an opening, strings stretched vertically across said 20 opening and secured to the back and neck, and a sounding box disposed between said back and neck, and on one side of certain of said strings, with one of its sides in engagement with said pillar, said sounding box being provided with a 25 hollow resonant chamber and having a plurality of openings opening outwardly thereof.

5. A harp having a hollow pedestal, pillar and back forming resonant chambers, said back and pedestal being provided with sound releasing 30 openings, and a sounding box having a vertically disposed resonant chamber, said sounding box being positioned in the harp opening and connected to said back and pillar and disposed along one side of the base strings of the harp to cooperate 35 with said aforementioned resonant chambers in producing deep melodious tones.

6. In a harp of conventional shape provided with strings stretched vertically between the neck and sounding board, a sounding box adapted to be 40 positioned in a harp opening and to be disposed along one side of its base strings, said sounding box adapted to be connected to the pillar, board and neck of the harp, and said pillar and board being provided with sound releasing openings 45 communicating with the hollow interior of said parts to cooperate with said sounding box to produce deep melodious tones.

WALTER VANTWILLER A. FRANKLIN.
